CHARLES STEPHEN MILNE, OF DEPTFORD, LONDON, ENGLAND

ACETYLENE GENERATOR

Application filed April 25, 1931, Serial No. 532,935, and in Great Britain April 30, 1930.

This invention relates to improvements in or connected with acetylene generators, more particularly to improvements in means for conveying and feeding calcium carbide from a hopper or the like to a generator and has for its object inter alia to increase the efficiency and safety in operation of such generators.

According to the present invention there is provided a feeding device for acetylene generators in which calcium carbide is fed by means of a conveyor from a hopper to the generating chamber characterized by the provision of sealing means for sealing the hopper from the conveyor chamber and/or generating chamber so as to prevent access of air thereto from the hopper. Means are preferably provided for preventing discharge of calcium carbide from the conveyor to the generating chamber, when it is desired to open the hopper.

Means are also preferably provided whereby it is impossible to open the hopper for replenishing for example until the means have been operated for preventing discharge of carbide into the generating chamber and operation of the conveyor has been discontinued. The said sealing means may be operated from the same actuating mechanism as that which operates the means for preventing opening of the hopper so that the sealing means also cannot be operated to seal the conveyor and generating chamber from the hopper until feeding of the carbide into the generating chamber has been interrupted.

The means for feeding or conveying the calcium carbide from the hopper or the like to the generating chamber may comprise a carrier, belt, chain or the like or may comprise bars, chains or the like caused to traverse along a bed plate or platform upon which the calcium carbide is fed from the hopper. Said conveyor may be operated by any suitable means, such as an electric or other motor, although I preferably employ a water-motor which may be operated from the mains and the discharge therefrom may be led into the generating chamber. Such

water motor may be adapted for automatic operation, thus a valve in the supply pipe may be operated by float controlled mechanism or by rise and fall of a gas holder. The discharge from the water motor in addition to feeding the generator chamber may also serve for removing sludge from such chamber.

The means for interrupting operation of the carbide conveyor or feeding means may comprise any suitable clutch mechanism included in the transmission between the motor and the conveyor and the lever or the like which operates such clutch may also operate a shutter, valve or the like adapted to close the discharge chute from said conveyor to the generating chamber. In this way it will be appreciated that movement of the conveyor is prevented even though the motor should be in operation and further that carbide is prevented from falling from the conveyor into the generator.

A valve, shutter or the like is preferably provided at the base of the hopper whence the carbide is fed to the conveyor and the lever or the like operating such shutter may be so interconnected with the means interrupting the conveyor that the shutter cannot be closed until such time as operation of the conveyor has been interrupted. It is to be observed that such shutter makes a gas tight joint preferably on to a seating of rubber or other suitable material and so prevents access of air to the conveyor chamber and consequent undesirable admixture with the acetylene during replenishing the hopper. Such shutter may be so arranged that during operation of the conveyor, agitation of the carbide is caused so as to facilitate uniform feeding of carbide thereto.

Any suitable man-hole, cover or the like may be fitted to the carbide hopper and I preferably provide means for preventing removal of such closure until the shutter or the like over the discharge orifice has been closed. Thus a system of links operated by the control of said shutter may be adapted to move an interrupter or locking device associated with said closure.

Means according to the present invention may be associated with any desired acetylene generating chamber.

In order that the invention may be well understood a preferred embodiment thereof will be described by way of example only with reference to the accompanying drawings, in which:

Figure 1 is a section through a preferred form of a complete generator.

Figure 2 is an elevation at right angles to the view shown in Figure 1.

Referring to the drawings a hopper 1 for receiving and discharging calcium carbide is provided with a removable closure 2 at the top and a flap valve 3 pivoted at 4 at the base, adapted to open and close a discharge opening 5. The pivot 4 preferably comprises a pin and slot connection so that the flap 3 can not only rotate about one edge but is also movable at right angles to the plane of the opening in the base of the hopper 1. The flap 3 is preferably provided with, or is adapted to fit on to a rubber or the like washer or seating so as to provide a gas tight closure. The discharge opening 5 opens into a conveyor chamber 6 in which is an endless conveyor chain 7 passing over sprockets 8, 9. The conveyor chain 7 is provided with suitable transverse ribs or chains 10 for the purpose of positively urging the carbide along the bed. The flap valve 3 is arranged so that when it is open it rests upon the conveyor bed 7, the ribs 10 of which cause the valve to vibrate, i. e. to rise and fall to a slight extent. Mounted on the flap 3 are one or more prongs 11 which project into the mass of carbide in the base of the hopper and the aforesaid agitation of the flap and of the prongs prevents the carbide from wedging in or bridging over the discharge opening 5, thus ensuring uniform discharge of carbide from the hopper.

A rock shaft 12 rotatably mounted in the upper part of the casing of the conveyor chamber 6 carries a member in the form of a lever cam or plate 13 within the chamber and an operating lever 14 external to the chamber and parallel with the member 13. It will be seen that when the lever 14 is in its lower position as shown in Figure 1, the member 13 holds the flap 3 in closed position but if the lever 14 is rotated clockwise (Fig. 1.) the member 13 is rotated and allows the flap 3 to open. Rigidly secured to the shaft 12 is a short lever 15 hingedly (Fig. 2.) connected at 16 to a link 17 hingedly connected at its other end to another short lever 18 mounted on a rock shaft 19 mounted on the hopper at its widest part. The shaft 19 carries a short lever 20 connected to a link 21 hingedly connected at its other end to a short lever 22 mounted on a rock shaft 23 at the top of the hopper

1. The rock shaft 23 carries a lever 24 bent at right angles and carrying at its extremity a cap 25 adapted to fit over screw means 26 for securing and releasing the closure 2. It will be seen that when the lever 14 is in position as shown in Figure 1 the cap 25 is removed from the closure 2 and its securing means 26 but that if the lever 14 is moved so as to allow the flap 3 to open the cap 25 is moved into position to cover the closure 2 and its securing means. Thus the hopper cannot be opened when the flap 3 is closed.

A rock shaft 27 is mounted so as to extend through the conveyor chamber above the conveyor and near the forward end thereof and carries a flap 28 adapted to prevent material from being discharged from the conveyor when the flap is in the position shown in Figure 1 with its lower edge in contact with the conveyor. The flap is actuated by an operating lever 29 carried by the rock shaft 27 externally of the conveyor chamber 6. Pivottally mounted on the lever 29 is a rod 30. This rod 30 is adapted to engage in a hole through the lever 14 and the rock shaft 12 when the lever 14 is in its upper position and when the lever 29 is in position to hold the flap 28 open. Thus when both flaps 3 and 28 are in open position the flap 3 cannot be closed until flap 28 has been closed by moving the lever 29 to its forward position shown in Figure 1 whereby the water engine is declutched from the conveyor drive shaft 34 as hereinafter described and the rod 30 is retracted from the hole in the rock shaft 12 to free lever 14 for movement. This means also that the closure 2 cannot be removed until the flap 28 has been closed to prevent further discharge of carbide from the conveyor and flap 3 has been closed to prevent the escape of gas from the conveyor and/or generating chamber.

The conveyor chain 7 is driven by means of a water motor 31 driven from the mains. The water motor is of the piston type and the piston rod 32 intermittently rotates a ratchet wheel 33 mounted on a shaft 34 which carries the sprocket wheels 8, by means of a suitable pawl. Means are provided for throwing the pawl out of engagement with the ratchet wheel 33 upon actuation of the lever 29 to close the flap 28. These means comprise a lever 38 carried by the rock shaft 27, connected by a link 35 to a lever 36 mounted on a rock shaft 37. Rotation of the rock shaft 37 causes rotation of a cam 39 which lifts the pawl out of engagement with the ratchet wheel 33 so that the operation of the conveyor is discontinued.

In operation the carbide is discharged from the conveyor into a chute 47 which dips below the water level in a generating chamber 48. The carbide descends from

the chute on to an inclined surface 40 and thence on to a grid 41. The water for the gas generation is supplied from the motor 31 by means of a pipe 42. The lime produced from the reaction is carried as a sludge round a baffle plate 43 through a water trap 44 and out of a discharge pipe 45.

The operation of the plant is as follows: Assume that the hopper is charged with carbide, the closure 2 is in place, the flaps 3 and 28 are open and the conveyor is feeding carbide into the generating chamber 48. If now it is desired to recharge the hopper, the lever 29 is first moved into the position shown in Figure 1 so as to stop the conveyor and to close the flap 28. The lever 14 is thereby freed and is then actuated to close the flap 3 and thus seal the conveyor chamber and therefore the generating chamber from the hopper. Actuation of the lever 14 also causes the cap 25 to be removed from its protective position over the closure 2 and its securing means 26. The closure 2 can then be removed and a fresh charge introduced. The closure 2 may then be replaced and the cap returned to its position and at the same time of course the flap 3 is opened.

Preferably however, in order further to prevent any possible admixture of air with the acetylene, prior to replacing the closure 2, lever 14 is rotated anti-clockwise a short distance to a stop point provided on the quadrant 46 which eases flap 3 so that it no longer makes a gas tight joint on the mouth of the hopper 5 and therefore permits the acetylene retained under slight compression in the conveyor chamber 6 to escape through the interstices between the carbide in the hopper 1 and drive out the air therefrom, thus obtaining complete freedom from air throughout the whole generating apparatus.

The required amount of movement of lever 14 to perform this operation is insufficient to cause any appreciable movement to cap 25 or to cause it to prevent access to closure 2 and its securing means 26.

The closure 2 is then replaced and secured after which lever 14 is rotated in an anti-clockwise direction the remainder of its travel, opening flap 3 and moving cap 25 to its protective position over closure 2.

The flap 28 is then opened by actuation of the lever 29 and simultaneously the conveyor is set in operation.

Any desired inspection door or doors for facilitating cleaning of the apparatus may of course be provided thus for instance I preferably provide a door in the wall of the generator through which the complete conveyor unit may be easily withdrawn and inserted when desired.

The operation of a generator incorporating feeding means as above set forth is substantially fool proof by reason of the provision of means for ensuring the operation of

the controls in the correct order, and further the apparatus is very efficient in operation by reason inter alia of the uniform feeding of the carbide and the prevention of access to the acetylene of air during the charging process.

In a modification of the above example an electric motor for example may be used in place of the water motor and in such cases a pump or the like may be used for feeding water to the generator and for removing sludge therefrom if desired.

Whilst I have hereinbefore given one example of apparatus according to this invention, it is to be understood that the particular details and arrangement of parts may be varied or modified without departing from the scope thereof, thus for example the conveyor chamber may be in direct communication with the generating chamber instead of being separated therefrom by the water sealed chute 47. Further the conveyor and/or the platform over which conveying means travel may be of any desired size and shape, thus for instance curved bars may be adapted to traverse a concaved bed or platform; further, generators incorporating my invention may be so arranged that automatic change over from one generator to another may be effected.

I claim:

1. An acetylene generator comprising a carbide hopper, a conveyor chamber communicating therewith, a conveyor in said conveyor chamber, a generating chamber communicating with said conveyor chamber, gas tight sealing means for sealing said hopper from said conveyor chamber and means for interrupting and preventing discharge of carbide from the conveyor to the generating chamber, the said sealing means being so associated with the means for interrupting and preventing discharge of carbide from the conveyor that they can not be operated to effect a seal until the discharge of carbide from the conveyor has been interrupted.

2. An acetylene generator comprising a carbide hopper, a conveyor chamber communicating therewith, a conveyor in said conveyor chamber, a generating chamber communicating with said conveyor chamber, gas tight means for sealing said hopper from said conveyor chamber, a closure for said hopper, protective means for preventing opening of the hopper, common control means for the protective means and the sealing means, and means for interrupting and preventing discharge of carbide from the conveyor, the said common control means being so associated with the means for interrupting and preventing discharge of carbide from the conveyor that they can not be operated to effect a seal until the discharge

of carbide from the conveyor has been interrupted.

3. An acetylene generator comprising a hopper, a conveyor chamber communicating therewith, a conveyor within said conveyor chamber, a generating chamber communicating with said conveyor chamber, a flap valve at the base of the hopper for effecting a gas tight seal of said hopper from said conveyor chamber, a closure at the top of said hopper, protective means for preventing opening of the hopper and common control for the protective means and the flap valve.
- 15 4. An acetylene generator comprising a hopper, a conveyor chamber communicating therewith, a conveyor within said conveyor chamber, a generating chamber communicating with said conveyor chamber, a flap valve at the base of said hopper for effecting a gas tight seal of said hopper from said conveyor chamber, a closure for said hopper, a protective cap for preventing opening of the hopper, a control lever for operating the flap valve and link and lever mechanism connecting said control lever with said cap.
- 20 5. An acetylene generator comprising a carbide hopper, a conveyor chamber communicating therewith, a conveyor in said conveyor chamber, a generating chamber communicating with said conveyor chamber, a flap valve at the base of said hopper for effecting a gas tight seal of said hopper from said conveyor chamber, a closure for said hopper, a protective cap for preventing opening of the hopper, a control lever for operating the flap valve, link and lever mechanism connecting said control lever with said cap, means for interrupting and
- 25 40 preventing discharge of carbide from the conveyor, a locking means for locking said control lever, said locking means being so

associated with the means for interrupting and preventing the discharge of carbide from the conveyor that actuation of the latter releases said control lever for operation.

6. An acetylene generator comprising a carbide hopper, a conveyor chamber communicating therewith, a conveyor in said conveyor chamber, a generating chamber communicating with said conveyor chamber, a flap valve at the base of said hopper for effecting a gas tight seal of said hopper from said conveyor chamber, a closure for said hopper, a protective cap for preventing opening of the hopper, a common control lever for the protective cap and the flap valve, means for interrupting and preventing the discharge of carbide from the conveyor, a control lever for said last mentioned means, means for locking the control lever of the protective cap and sealing means in position to maintain the cap in protective position and to maintain the flap valve at the base of the hopper open, said locking means being actuated by said second mentioned control lever.

7. An acetylene generator comprising a carbide hopper, a conveyor chamber, communicating therewith, an endless belt conveyor chamber upstanding projections on said belt conveyor, a generating chamber communicating with said conveyor chamber, a flap valve at the base of said hopper for effecting a gas tight seal of said hopper from said generating chamber, said flap valve resting on said belt conveyor when in open position and carrying prongs which project into the carbide in the base of the hopper whereby agitation of the flap valve by the projections on the conveyor prevent bridging of the carbide in the base of the hopper.
